Robert W. Whitehurst
By his Atty
Chas B. Mann

UNITED STATES PATENT OFFICE.

ROBERT W. WHITEHURST, OF NORFOLK, VIRGINIA.

CULTIVATING-PLOW.

SPECIFICATION forming part of Letters Patent No. 236,743, dated January 18, 1881.

Application filed November 29, 1880. (No model.)

To all whom it may concern:

Be it known that I, ROBT. W. WHITEHURST, a citizen of the United States, residing at Norfolk, in the county of Norfolk and State of Virginia, have invented certain new and useful Improvements in Cultivating-Plows; and I do hereby declare the following to be a full, clear, and exact description of the invention, such as will enable others skilled in the art to 5 which it appertains to make and use the same, reference being had to the accompanying drawings, and to letters or figures of reference marked thereon, which form a part of this specification.

15 The present invention relates to certain improvements in cultivating-plows, which will first be described, and then designated in the claim.

In the drawings hereto annexed, Figure 1 is 20 a side view of the plow without the beam or handles. Fig. 2 is a top view of the same. Fig. 3 is a cross-section of rear standard, showing the sweep-holders. Fig. 4 is a perspective of the sweep-holder. Fig. 5 is sweep.

25 The letter A designates the standard; B, the point, and C C the two mold-boards. It will be noticed that one mold-board laps over the edge of the other, as shown plainly in Fig. 2, whereby the cutting-edge *a* is formed wholly 30 on one board, and is devoid of crevice or joint, as in the case of those cultivators whose two mold-boards have the abutting edge of each beveled alike, forming the cutter of an edge of each board.

35 By the arrangement herein shown the objection referred to, of the crevice at the cutting-edge, is avoided. In the present instance a bolt, *b*, is passed through the two mold-boards and standard; but they may be se- 40 cured otherwise.

A land-bar, D, extends from the foot rear- 45 wardly, and is shod on its under side with a plate, D'. To the upper side of the land-bar is attached a rear standard, E, which rises up and extends obliquely rearward. The upper end of this rear standard and the top of the front standard are connected by a bar, F, to a portion, F', of which the draft-beam (not shown) is secured.

50 The handles, of which only a broken part of one is shown, are attached to the rear stand- 55 ard, one on each side. The lower end of the

handle G rests in the sunk panel or socket *c* on the side of the standard, where it is bolted through the hole *d*. At the upper part of the rear standard, on each side, is a lateral-projecting shoulder or lug, *e*, in such position as to serve as a support for the handle which rests upon it. A bolt-hole, *f*, through the standard, near the lugs, provides for bolting the two handles together. By the lug which projects from each side of the standard great stability is given to the handles.

A portion of the rear standard, E, has a vertical slot, *g*, and the edges of the standard 65 parallel with the slot are raised, as at *h*. (Shown plainly in cross-section in Fig. 3.) Each side of the standard is provided alike with the raised edges *h*, which form a guideway.

A right-angled sweep-holder, I, has a slot, *k*, on one part, the edges of which are straight and parallel, and the said part is of width to rest between the raised edges *h* on the standard E, where it may have a vertical sliding 75 movement, the slot *g* in the standard, and the slot *k* in the holder, through which a bolt, *m*, passes, affording every facility for the separate or independent vertical adjustment of either of the two holders. The other part of 80 the right-angled holder has a hole, *n*, for a bolt, *n'*, on which the sweep or wing L pivots, and said part also has a notched or toothed edge, *p*, which is concentric with the pivoting-hole *n*.

The sweep or wing L is a blade, having at 85 one end a head through which the bolt *n'* passes. The broad sides of the blade are in an oblique or angular position with respect to the head, in order to better turn or throw off 90 the dirt that falls from the mold-board. The lower edge of the blade next to the head (see Figs. 1 and 5) forms a shoulder or point, *q*, which engages with one of the notches *p* on the holder.

It will be seen, by removing the nut from 95 the bolt *n'*, the point *q* of the sweep may be set in either of the notches *p* of the holder, and thus the sweep may be adjusted forward or back in any position desired, to throw more 100 or less dirt, and yet the means of adjustment are such that the sweeps move in the same horizontal plane.

I am aware that sweeps have been arranged

to permit of adjustment forward and back; but such as I am familiar with are so arranged that when moved back the outer end is also raised, and when moved forward they are lowered.

5 The right-angled holder herein shown provides for all manner of adjustments for the sweep within the range of both vertical and horizontal, so that a greater range of work may be done than heretofore.

One sweep may be worked high up and the other low down, and one may be extended to throw dirt on one side while the other may be adjusted back and, by causing some draft, 15 made to act simply as a counter-balance.

Having described my invention, I claim and desire to secure by Letters Patent of the United States—

In a cultivating-plow, the combination, with the standard E, of the sweep-holder I, having 20 the notches p, and adapted to be vertically-adjusted on the plow, and the sweep L, having a tooth or point, q, for engagement with the notches, whereby the sweep may be adjusted vertically and forward and back with- 25 out changing its horizontal plane, substantially as shown and described.

In testimony whereof I affix my signature in presence of two witnesses.

ROBERT W. WHITEHURST.
